UNITED STATES PATENT OFFICE.

THOMAS W. McMICKEN, OF HUMBLE, TEXAS.

SAW FILER AND GUMMER.

1,329,423.

Specification of Letters Patent.

Patented Feb. 3, 1920.

Application filed June 29, 1917. Serial No. 177,774.

To all whom it may concern:

Be it known that I, THOMAS W. McMICKEN, a citizen of the United States, residing at Humble, in the county of Harris and State of Texas, have invented certain new and useful Improvements in Saw Filers and Gummers, of which the following is a specification.

This invention relates to new and useful 10 improvements in a saw filer and gummer.

The object of the invention is to provide a device of the character described adapted for the purpose of sharpening and gumming the teeth of circular saws particularly such 15 saws as are used in cotton gins.

The improvement herein described relates to an attachment to a saw filer and gummer, a patent on which was heretofore issued to me by the United States Patent Office on the 20 18th day of April, 1916, No. 1,180,270, said attachment consisting of a guide which embraces the rim of the saw while being operated upon and prevents the vibration of said saw while the files are operating 25 thereon.

In using the saw filer and gummer above referred to, I have found that circular gin saws when being filed and gummed, have a tendency to vibrate or move back and forth 30 on account of the pressure of the files against the same, thus preventing the true operation of the files in filing and gumming the teeth and I have added the attachment herein described and claimed, to embrace 35 the rim of the saw so as to hold it firmly against said file, thus conducting to the true operation of the file.

With the above and other objects in view, the invention has particular relation to certain 40 novel features of construction, operation and arrangement of parts, an example of which is given in this specification and illustrated in the accompanying drawings, wherein:—

45 Figure 1 shows a side elevation of the device showing certain parts broken away for the sake of clearness.

Fig. 2 is an enlarged fragmentary side elevation, and

50 Fig. 3 is a fragmentary plan view of the gummer and saw guide.

Referring now more particularly to the drawings, wherein like numerals of reference designate similar parts in each of the 55 figures, the numeral 1 refers to a supporting base upstanding from which is the brace 2

and mounted upon which are the bearings 3, 3, in which the file rods 4, 4, reciprocate. The forward ends of these rods carry the respective files 5, 5, which are reciprocated 60 through a mechanism fully described in the patent hereinbefore referred to and which are provided for the purpose of operating upon and filing the saw teeth. The numeral 6 designates a gummer which is disk-like in form having a flat under surface and a beveled upper surface, said under and upper surface being roughened or serrated as shown in Figs. 2 and 3. This gummer has a central orifice which receives the upper 65 end of the shaft 7, upon which the gummer rotates. A beveled pinion 8 is provided, having a central orifice which also receives the upper end of the shaft 7 and this pinion is connected to and rotates with the gummer 70 6 and the gummer and pinion 8 are secured against detachment from the shaft 7 by means of a lock nut 9 which is screwed onto the upper end of the shaft 7 and the pinion 8 is in mesh with and receives rotation from a pinion 10 which is fixed on the 75 front end of the shaft 11. The shaft 11 extends through and has a bearing in the slidable block 12, said block also supporting the gummer and being provided with a vertical bearing 13 which receives the shaft 7. The block 12 is reciprocated as fully described in said patent above referred to so as to bring the gummer into and out of contact 80 with the saw teeth.

The forward end of the bearing 13 is rounded off and a guide 14 is provided, having an arcuate base which fits the contour of the rounded end of the bearing 13, said guide being secured to the bearing by means 85 of set screws which pass through the base and are screwed into the bearing; said guide is bifurcated, forming two fingers which closely embrace the saw underneath the gummer and hold said saw steady and prevent it from vibrating while the files and particularly the gummer are operating 90 thereon. This guide is very essential as without it, the saw will vibrate, causing an irregular operation of the files and gummer 95 thereon and preventing the true filing and gumming of the teeth. These fingers are of such length that they will not be entirely withdrawn from the saw upon withdrawal of the gummer from operative contact with the teeth, but will at all times hold the gummer and saw in perfect alinement. The 100 105 110

guide is secured to the bearings 13 by means of set screws 15 so that when the fingers become worn allowing the saw too much play, the guide may be easily detached and a new one substituted therefor.

What I claim is:

A device of the character described including a rotatable disk-like saw gummer, a supporting bearing therefor for holding the 10 gummer against the saw, and whose outer end is rounded off, a detachable guide carried by said bearing formed with an arcuate base which fits against said rounded end and is detachably secured thereto, said guide 15 having spaced fingers which are adapted to

rest against the saw on opposite sides of the teeth being operated on to prevent the vibration of the saw while being operated on by said gummer and a mechanism for automatically withdrawing said gummer from the 20 saw, said fingers being of a sufficient length to embrace said saw when the gummer is withdrawn therefrom.

In testimony whereof I have signed my name to this specification in the presence of 25 two subscribing witnesses.

THOMAS W. McMICKEN.
